UNITED STATES PATENT OFFICE.

HARRY OSTROVSKY, OF BRYN ATHYN, PENNSYLVANIA.

APPARATUS FOR PROMOTING FLEXIBILITY OF THE JOINTS OF THE HANDS.

Application filed May 17, 1927. Serial No. 192,112.

My invention consists in new and useful improvements in apparatus for use by musicians in promoting the flexibility of the joints, and stretching the muscles and ligaments of the hands.

It is the object of my invention to provide a device of the above character which will affect practically every joint and muscle of the hands and fingers by a plurality of different operations and positions of the various elements comprising the apparatus.

It is a further object of my invention to produce a finger exercising device which will improve the circulation through the hands and fingers.

With the above and other objects in view which will appear as the description proceeds, my invention consists in the novel features hereinafter described in detail, illustrated in the accompanying drawings, and more particularly pointed out in the appended claims.

Referring to the drawings in which numerals of like character designate similar parts throughout the several views,

Fig. 1 is a plan view of the apparatus, showing the oscillating plates with the finger gripping members in dotted lines mounted thereon.

Fig. 2 is a view in side elevation, showing the bracket arrangement for supporting the wrist engaging yoke, partly broken away.

Fig. 3 is a sectional view taken on line 3-3 of Fig. 2.

Fig. 4 is a sectional view taken on line 4-4 of Fig. 1.

Fig. 5 is a sectional view of one end of the device, showing the plates in different positions.

Fig. 6 is a lateral cross section showing the bracket adjuster and plate oscillating gear.

Figs. 7 and 8 and 9 are plan, sectional and end views respectively, of the operating lever.

Figs. 10 and 11 are plan and sectional views, respectively, of the wrist engaging yoke, showing the cushion in place.

Fig. 12 is a view of the cushion adapted to be secured in said yoke.

Fig. 13 is a plan view of a finger gripping member.

Fig. 14 is a sectional view of the plate engaging portion of said member.

Fig. 15 is a section taken at right angles to Fig. 13.

Fig. 16 is a longitudinal section of the finger gripping member, showing the loop tightening means, and

Fig. 17 is a detail sectional view of the auxiliary tightening means.

Figs. 18, 19 and 20 show modifications of the adjustable yoke member.

In the drawings, 1 represents the main body of the device which is in the form of a rectangular box having bottom, end and side walls. 2 represents a plate member bent down along its side edges, which bent down portions are provided with bars 3 having downwardly extending teeth along the lower edges thereof, and adapted to be operatively engaged by a toothed gear 4 on the inner end of the operating knob 5 which is keyed on the outer end of a rotating shaft 6, mounted transversely of the body 1 in apertures in the side walls thereof, see Fig. 6.

7 designates pawl members pivotally mounted on the side walls of the body, adjacent the operating knobs 5, and adapted to engage the teeth of the gear member 4, when it is desired to retain the oscillating plate 2 in a fixed position.

Opposite the oscillating plate 2, and hinged at the other end of the body portion, is a plate 8 adapted to be swung upwardly and back, and retained in predetermined positions as will be hereinafter described.

In each of the plates 2 and 8, I provide apertures 9, and key slots 10 adapted to receive the lugs on the finger gripping members, hereinafter referred to more in detail.

Beneath the hinged plate 8, and within the side walls of the body 1, I provide another hinged plate 11, the free end of which normally rests upon stops 12 secured on the inner faces of said side walls. This plate is bent downwardly at each end, forming arc-shaped flanges 13 adapted to register with, and engage rollers 14 along the inner edge of plate 2, when said plate 11 is raised upwardly on its pivot, as clearly shown in Fig. 2, whereby when said plate 2 is oscillated, on the body 1, the hinged plate 11

will be caused to reciprocate up and down therewith.

15 represents a substantially U-shaped yoke having an angularly disposed horizontal face, slidably mounted in brackets 16, and retained in place by covers 17. Along the outer edge of each leg of the yoke 15, I provide a series of ratchet teeth 18 adapted to be engaged by pawls 19, mounted in said brackets, whereby when said yoke is pushed downwardly in the brackets 16, against the tension of springs 20, said yoke may be retained in the desired position. By means of the lever 21, the pawl may be caused to disengage the ratchet teeth 18, allowing the springs 20 to return said yoke to its uppermost position.

The angular face of the yoke 15 is provided with key slots 22, and threaded apertures 23, the latter being adapted to receive screws 24 for slidably securing a plate 25 in place thereon. This plate is provided with apertures 26 adapted to register with the key slots 22 in the face of the yoke, and slots 27, through which said screws 24 are adapted to pass to slidably retain said plate 25 in place. In order to maintain the plate 25 in engaging position, I provide a spring 28 on a short shaft 29 secured to the yoke 30, 15 and engaging the bent end of said plate.

30 represents a wrist cushion having secured to its upper surface a plate 31 provided with lugs 32 having enlarged heads, and adapted to be passed through the key slots 35 22 in the face of the yoke 15, and the apertures 26 in the slidable plate 25, when the latter is pushed inwardly against the pressure of the spring 28. It is obvious that when the spring is released, said plate will be forced outwardly again, throwing the apertures 26 out of alignment with the key slots 22, the edges of said apertures thereby engaging the lugs 32 beneath said enlarged heads to retain said cushion in place on the yoke, as clearly shown in Fig. 11.

45 The brackets 16 retaining the yoke 15, are pivotally mounted in the side walls of the body 1 on a shaft 33, and are made adjustable by means of a plurality of apertures 34 adapted to be engaged by a spring actuated plunger 35, operated by a knob 36. It will thus be seen that any desired adjustment of the position of the yoke may be accomplished by withdrawing the plunger 35 from its engaging position and swinging the brackets 50 16 on the shaft 33 until the desired position is obtained, and then allowing said plunger to engage a new aperture.

55 37 designates the finger gripping members, each of which consists of a main body portion bent upwardly at its longitudinal extremities, one of which bent up portions is cut out along its edge in the form of a ratchet face 38. Between the bent ends of said body, I secure a face plate 39 having a

slot 40 therein. Pivots mounted on this face plate 39 is a lever 41 provided with a screw 42 slidable in a slot 42^a in said lever, and adapted to pass through and register with said slot 40, the inner end of said screw 70 being threaded to engage apertures in plates 43 within the body portion of the member 37. 44 represents a strip of canvas or other suitable material, the ends of which are secured together between the plates 43 with- 75 in said body member forming a loop 45 along the longitudinal edge of the member 37 for receiving the finger of the operator. 46 represents a finger support which extends through the loop 45, and is secured at 80 its outer extremities to the bent portions of the body member. It will thus be seen that when the lever 41 is swung downwardly on its pivot, the screw 42 will be forced downwardly therewith through the 85 slot 40, which in turn will cause the plates 43 to draw the ends of the canvas strip downwardly, causing loop 45 to tighten around the finger of the operator, the lug 47 on said lever, engaging the ratchet teeth 90 38 to retain said loop in gripping position.

In order to obtain a more minute adjustment of the finger gripping loop, I provide an auxiliary lever 48 pivoted on the screw 42, and having at one end, a cam arrangement 49 adapted to bear against a projection 50 on said main handle 41, whereby when said auxiliary handle is swung downwardly, the cam 49 will engage the projection 50, and cause the screw 42 to be forced 100 downwardly through slot 42^a, to further tighten the loop 45. This auxiliary handle is also provided with a ratchet arrangement 50^a for retaining the same in the desired position.

105 The finger gripping member 37 is provided at its extremity opposite the loop 45, with a pair of lugs 51 mounted on a plate 52 which is bored centrally thereof to receive a short shaft 53 on which is rotatably mounted a cam arrangement 54. The body portion of the finger gripping member is provided with apertures 55, registering with said lugs 51, and through which said lugs are adapted to extend when the plate 52 is forced downwardly by the cam 54, against the tension of the springs 56 for the purpose hereinafter described.

110 57 represents an operating lever having at one end thereof, a pair of spring actuated gripping fingers 58, and a stationary lug 59, whereby said lever is adapted to be locked in place on the operating knob 5, said gripping fingers 58 and lug 59 engaging the desired recesses 60 in the periphery of said 115 knob, as shown in dotted lines in Fig. 2.

61 represents an ear integral with the main body portion of the finger gripping member 37, having a squared aperture there- 120 in for engaging the hook member 62 on the 125

inner edge of the plate 2 for the purpose hereinafter set forth.

The use and operation of my device are as follows:

- 5 When it is desired to stretch the web between the fingers, the two finger gripping members 37 are locked in place, one on each of the plates 2 and 8 by inserting the lugs 51 which are in the down position in the 10 desired aperture 9, and key slot 10 in said plate, as shown in dotted lines in Fig. 1. The fingers are then inserted one in each loop 45, with the palm turned upwardly, and the lever 41 is swung downwardly on its 15 pivot, tightening said loop around the finger in the manner heretofore described.

The operating lever 57, having been locked in position on the knob 60, as shown in dotted lines in Fig. 2, is then swung backward and forward with the free hand of the operator to oscillate the plate 2, the plate 8 and the finger gripping members locked thereon, remaining stationary. It will thus be seen that as the plate 2 oscillates, the 25 fingers of the operator will be drawn apart and the web between the same stretched.

Assuming that the operator desires to stretch the joints of his fingers. The finger gripping members 37 are removed from the 30 plates, and the ear 61 of one of the gripping members is hooked on to the hook member 62 on plate 2, the cam lever 54 on said gripping member having been turned to the position shown in Fig. 14 to retain the lugs 51 in retracted position, whereby the plane flat surface of the body portion of said gripping member is presented to the upper surface of the plate 8.

The hand of the operator is then passed 40 through the yoke 15 with the palm down, resting on the rounded edge of the body 1, and the finger to be stretched is inserted in the gripping loop 45 which is then tightened thereon. In order to secure the wrist in the 45 proper position, the yoke 15 with the wrist cushion 30 in place thereon, is pressed downwardly in the brackets 16, and retained in the wrist engaging position by means of the pawl and ratchet arrangement 18 and 19. The operating lever 57 is then oscillated in 50 the manner heretofore described, which in turn causes the plate 2 to slide backwards and forwards on the body 1, and with it, the finger gripping member 37 which is free to slide on the plate 8.

The fingers are then released from the gripping member 37, and the wrist from the yoke 15, by turning the lever 21 to disengage the pawl 19 from the ratchet teeth 18, 60 the spring 20 causing said yoke to return to its normal position.

To flex the fingers backwardly and upwardly to stretch the ligaments of the same, the plate 8 is swung back on its pivot to the 65 position shown in Fig. 2, and the hinged

plate 11 is swung upwardly on its pivot, the knob 5 being turned in clock-wise direction, until the rollers 14 on the edge of the plate 2 engage the arc-shaped flanges of said plate 11. The hand of the operator is then 70 inserted through the yoke 15 with the palm resting downwardly on the upper surface of the plate 8, the fingers resting on the oscillating plate 11. The yoke 15 is then pressed downwardly as heretofore described, 75 to secure the hand in place. When the operating lever 57 is swung backwards, and forwards, to oscillate the plate 2, the rollers 14 engaging the arc-shaped flanges on the plate 11 cause said plate to be oscillated on 80 its pivots, bending the fingers upwardly.

The plate 8 may likewise be given a rotary oscillation on its hinges by means of the oscillating yokes 63 rotatably mounted in each of the brackets 16, and operatively 85 connected together for this purpose by means of a connecting yoke 64. This oscillation may be accomplished by placing the lever 57 through the medium of a squared hole 65 on the squared lug 66 of one of said 90 yokes 63, whereby when said lever 57 is swung backwards and forwards, the yokes 63 will be caused to oscillate, which in turn will raise and lower the plate 8 on its hinges.

It is obvious that numerous other exercising and flexing operations may be accomplished with my improved apparatus by merely changing the positions of the several elements comprising said apparatus.

In Figs. 18 to 20 inclusive, I have shown a modification of the bracket 16 and wrist engaging yoke 15, including a slightly different ratchet arrangement.

In this structure, the bracket 16 is mounted on a tube 70 which surrounds the rotary 105 shaft 33 and is provided with a slot 71 through which the operating lever 72 is adapted to be inserted, said operating lever being secured to the shaft 33. On the outer end of the shaft 33, I secure a pawl 73, 110 adapted to register with a series of ratchet teeth 74 on the inner edge of a cut out portion 75 intermediate the side edges of the yoke 15. The pawl is retained in engaging position by a suitable spring 80. In this 115 particular form of the invention, the lower ends of the legs of the yoke 15 are bent outwardly at substantially right angles to form arms 76, provided at their outer extremities with lugs 77. The cover 17 is modified 120 to accommodate this structure by providing at the upper extremity of the inner wall thereof, a lug 78, adapted to engage the upper end of a coil spring 79, the lower end of which is secured to the lug 77 on the leg of 125 said yoke, whereby said yoke is under a continuous upward pressure.

The operation of this modification is obvious. When the yoke 15 is pushed downwardly in the bracket 16, the pawl 73 en- 130

gaging the ratchet teeth 74, will retain said yoke in the desired position, and to release the pawl, the lever 72 is pushed downwardly to rotate the shaft 33, thus disengaging said pawl from said teeth.

From the foregoing it is believed that the construction, operation and advantages of the invention may be readily understood by those skilled in the art, and I am aware that changes may be made in the details disclosed without departing from the spirit of the invention as expressed in the appended claims.

What I claim and desire to secure by Letters Patent is:

1. Apparatus for promoting flexibility of the joints of the hands, comprising a main body, a slidable plate mounted thereon, means for imparting movement thereto, a second plate adjacent said slidable plate, finger gripping members adapted to be locked in place on both of said plates, whereby when said slidable plate is oscillated on said body, the fingers in said gripping members will be stretched.

2. Apparatus as claimed in claim 1, wherein in said means for imparting movement to said slidable plate comprises a rack mounted on the edge of said plate adapted to be operatively engaged by a pinion gear rotatably mounted in said main body, and a removable handle for oscillating said gear.

3. Apparatus for promoting flexibility of the joints of the hands, comprising a main body, a slidable plate mounted thereon, means for imparting movement thereto, a hinged plate adjacent said slidable plate, and means for retaining the same in predetermined positions with respect to said body, a second hinged plate beneath said last named plate having means for operatively engaging said slidable plate, whereby when the latter is reciprocated longitudinally on said body, said second hinged plate will be caused to oscillate vertically on its hinges, and means for retaining a hand in palm down position with the fingers resting on said oscillating plate.

4. Apparatus as claimed in claim 3, wherein in said slidable plate is provided along one edge with rollers, said second hinged plate being provided with arc shaped flanges extending downwardly at right angles thereto, adjacent said rollers, whereby when said sliding plate is oscillated on said body, said rollers will engage said flanges and cause the plate supporting the same to reciprocate on its hinges.

5. Apparatus as claimed in claim 3, wherein in said hand retaining means comprises a yoke adjustably mounted on said body.

6. In a device for promoting digital dexterity, a finger gripping member comprising a body portion, a strip of flexible material having its ends secured together with

in said body portion, forming a loop along one edge thereof, means on said body portion for drawing the ends of said strip within said body to tighten said loop, and means for locking said member in engaging position.

7. In apparatus for promoting digital dexterity, a finger gripping member comprising a body portion, a finger engaging loop, a lever mounted on said body for tightening said loop, and means for locking said lever in predetermined positions.

8. Apparatus as claimed in claim 7, wherein in said finger gripping member is provided with an auxiliary loop tightening means.

9. Apparatus as claimed in claim 7, wherein in said finger gripping member is provided with a plurality of means for locking the same in different positions on said apparatus.

10. In apparatus for promoting digital dexterity, a hand retaining yoke, a pawl and ratchet arrangement in connection with said yoke, whereby the same is vertically adjustable on said apparatus, and means for adjusting said yoke longitudinally of said apparatus.

11. Apparatus as claimed in claim 10, wherein said means for longitudinally adjusting the yoke consists in brackets pivotally mounted on the body of said apparatus, and in which said yoke is slidably mounted, and means for locking said brackets in predetermined positions.

12. In apparatus for promoting digital dexterity, a pair of brackets adjustably mounted thereon, a yoke having downwardly extending legs slidable in said brackets, said legs being provided with ratchet teeth, pawl members mounted on said brackets and adapted to engage said ratchet teeth, means for disengaging said pawl from said teeth, and a spring for maintaining an upward pressure on said yoke.

13. Apparatus as claimed in claim 12, wherein said ratchet teeth are formed in recesses intermediate the side edges of the legs of said yoke, and said pawls extend within said recesses.

14. Apparatus as claimed in claim 12, wherein said ratchet teeth are formed in recesses intermediate the side edges of the legs of said yoke, and said pawls extend within said recesses, said yoke legs being bent outwardly at their lower extremities to form lugs, covers adapted to fit on said brackets over said legs, a lug in the upper portion of each of said covers, said springs being secured at their upper ends to said cover lugs and at their lower ends to said leg lugs.

15. Apparatus as claimed in claim 12, wherein said yoke is provided with a removable cushion.

16. In apparatus for promoting digital dexterity, a finger gripping member com-

prising a body portion, a strip of flexible material having its ends secured together between two plates within said body portion, forming a loop along one edge thereof, a lever pivoted on said body, operatively engaging said plates and adapted to draw the same downwardly to tighten said loop,

means for retaining the same in tightened position, lugs on said body portion for engaging different portions of said apparatus, and means whereby said lugs may be extended and retracted within said body. 10

In testimony whereof I affix my signature.

HARRY OSTROVSKY.
